UNITED STATES PATENT OFFICE.

WILLIAM M. DICKERSON, OF INDIANAPOLIS, INDIANA, ASSIGNOR OF ONE-HALF TO LEWIS W. HOLLOWAY, OF SAME PLACE.

BAND-SAW MILL.

SPECIFICATION forming part of Letters Patent No. 340,990, dated May 4, 1886.

Application filed February 8, 1886. Serial No. 191,253. (No model.)

To all whom it may concern:

Be it known that I, WILLIAM M. DICKERSON, a resident of Indianapolis, Marion county, Indiana, have made certain new and useful 5 Improvements in Band-Saw Mills, a description of which is set forth in the following specification, reference being made to the accompanying drawings, in the several figures of which like letters represent like parts.

10 My invention relates to an improvement in the mechanism for hanging and adjusting the mechanism which carries the band saw and regulates its tension upon the pulleys, and will be understood from the following description.

15 In the drawings, Figure I is a side view of of my device, partly in section; and Fig. II is a similar view, on a larger scale, of the lower parts thereof.

20 In detail, P is a hollow metal pillar, firmly bolted to a base, B.

s is a sliding plate or bar, which is allowed to move against one of the faces of the pillar P, and at the upper end of this slide s the 25 yoke y, which carries the upper pulley, p, is pivoted at the point 1. This yoke y, thus pivoted or hinged to the upper end of the slide s, provides bearings for the axle a of the upper pulley, p, and a lever, l, is connected to 30 one of the sides of this yoke, passing through an opening of corresponding size in the pillar P. w is a counter-balance, which is adjustable upon the end of this lever l, so as to equalize the weight caused by the overhang of the 35 yoke y and its load. On the lower end of this yoke is a small arm or projection, p², and connected with this arm is a ratchet, r, and pawl terminating in a screw, sc, which is pivoted at 2 to the outer end of a second lever, l', also 40 passing through the pillar P, and having its fulcrum on a pivot, 3. The outer end of this lever l' terminates in a right angle, and also carries a counter-balance or weight, w', the object of this weight being to assist in balanc-

45 ing the weight of the yoke, with its mechanism, when the saw is stretched. The screw sc terminates in a socket formed in the base b, which is connected with the screw, this base only resting upon the upper surface of the 50 arm of the bracket b', which is slightly inclined, so that the movement of the screw sc

simply moves the base up and down this incline, the base b being in no wise connected to the bracket b'.

p' is the lower saw-pulley, mounted upon 55 an axle, a', having bearings on one side in the bracket-arm b', and on the other side in a projection connected with the base of the frame-work.

f is a frame-work bolted to the face of the 60 slide s. This frame-work has two projecting lugs on its upper side, which are threaded to admit the adjusting-screws s', between which the arm p² passes, and below and within the body of the frame-work f are coil-springs sp 65 on either side of the arm p², and the ends of the frame are threaded to receive the tension-screws s'', which on their inner ends have followers bearing against the ends of the coil-springs. 70

The slide s is provided with the friction-screws 6 and 7, for bearing against the face of the pillar P and preventing the slide from falling downward while balancing the yoke.

The operation of my device is as follows: 75 The yoke y is drawn out or pushed in so as to bring the upper pulley, p, as near as possible in line with the lower pulley, and the screws s' s' are then adjusted so that their ends will be equidistant from each side of the arm p², 80 and not touching this arm. The friction-screws 6 and 7 during this operation are supposed to have been tightened against the face of the pillar P, the ratchet r and the screw connected therewith being loose. The saw is 85 then put on over the pulleys, and by means of the ratchet r and the screw sc the arm p² is forced up, carrying the yoke y and the pulley p, stretching the saw as much as desired upon its upper and lower pulleys. When this 90 is done, the counterpoises on the upper and lower levers, l l', are fastened by set-screws to the desired point on these levers, and the springs sp, by means of the screws on either side, are carefully adjusted so that the bearing on either side of the arm p² is the same, the upper screws, s', being left free from contact with the sides of the arm p², so that in case of any uneven or unequal pressure upon either edge of the saw, there will be provided 95 an elastic bearing by means of the springs on either side of the arm p, which is connect-

ed with the yoke which carries the upper pulley, the elasticity of the springs will resist such uneven pressure on the one side, and the elasticity of the spring on the other side will 5 in some measure equalize it, so that a rigid bearing or pressure on the arm p^2 is avoided by means of these compensating elastic springs, and I thus provide a counterpoise connected with the yoke y on one side, and a counterpoise connected with the screw sc at the bottom, steadyng the movement of the yoke mechanism at all times while the saw is in motion, and also providing an elastic bearing by means of the springs and adjusting mechanism, and by means of the screws s' , which will 15 allow a nicety of adjustment, keeping the saw-pulleys substantially in line with each other; and in case one side of the saw becomes more heated than the other side there is ready 20 means provided in the adjusting mechanism herein indicated for easing up the strain on that side of the saw.

I am aware that band saw pulleys carried in a yoke pivoted to a hollow pillar are not 25 new, and do not broadly claim the same as my invention.

What I do claim as my invention, and desire to secure by Letters Patent, is the following:

1. A band-saw mill wherein the upper pulley is carried in a yoke pivoted to a slide, s , connected with one face of a hollow pillar, P , the overhang of the yoke and its pulley counterbalanced by means of a primary lever connected to the inside end of said yoke, extending 35 outward past the supporting-pillar, and provided with an adjustable weight on such outer end, and further counterbalanced by a secondary lever connected with a screw mechanism operating upon the yoke-supporting bar 40 for bringing the pulleys in line, this secondary lever extending outward and provided also with an adjustable counter-weight, substantially as and for the purposes described.

2. A band-saw mill wherein the upper saw-pulley is carried in a yoke pivoted or hinged to the upper part of the supporting-pillar, provided with a counter-balance on the lower side of said yoke, and also provided with an arm which is connected with a ratchet for raising and lowering the yoke and the pulley it carries, such connecting-arm passing through a frame-work provided with one or more pressure-springs, furnishing an elastic bearing against the sides of such projecting arm for 50 keeping the upper and lower pulleys in line with each other, substantially as described.

3. A band-saw mill whose upper pulley is carried by a yoke hinged to the upper portion of a supporting-pillar and provided with a 55 lateral counter-balance on one side, a ratchet mechanism below such yoke, and connected with it so as to elevate the yoke and its pulley for giving tension to the saw when slipped on over the upper and lower pulleys, a second lever pivoted to the screw of such ratchet,

having a suitable counter-balance on its outer end, and adjusting mechanism connected with a frame-work bolted to the side of the supporting-pillar and provided with one or more coil-springs for furnishing an elastic bearing 70 to the sides of a projection from the upper part of the yoke, and a lower saw-pulley and bandsaw, all combined substantially as described.

4. The adjusting mechanism herein described, composed of a suitable frame-work, 75 f , bolted to the slide s , and provided with pressure-springs sp , contained in such frame, tension-screws s'' , operating upon such springs, adjusting-screws s' , between which the projection from the yoke passes, and a suitable 80 screw-and-ratchet mechanism connected therewith, the upper pulley-wheel, p , mounted in the yoke y , which is pivoted to the pillar P , the lower pulley-wheel, p' , having bearings in the lower bracket and base, the lifting mechanism composed of the screw sc and its ratchet, its lower end resting in the base b , adapted to slide on the inclined upper surface of the bracket b' , the yoke-bar p^2 , connected with the yoke y , the lever l , and its counter-balance w , all combined substantially as described.

5. A band-saw mill whose upper pulley is carried in a yoke hinged to the upper end of a supporting-pillar, such yoke and pulley balanced by a suitable counterpoise connected therewith, and one or more coil springs operating against either side of a projection below the yoke, in combination with adjusting-screws 95 above such springs, the upper and lower saw-pulleys mounted in suitable bearings, as herein described, the lifting-screw sc , with its ratchet resting upon the lower bracket, b , and operating against a supporting-bar on the under side of the yoke y , all combined substantially as 100 described.

6. In a band-saw mill, the yoke y , hinged to the slide s at one end and adapted to move upon the face of the pillar P , the upper saw-pulley, p , mounted upon an axle having bearings in the sides of such yoke, the lateral balancing-lever l , with its weight w , the yoke-supporting bar p^2 , connected with the ratchet mechanism, and a screw below pivoted at 2 to the secondary lever l' , provided with a counter-balance, w' , the lower pulley, p' , mounted upon the axle a' , having bearings in the bracket-arm b' and a projection from the frame, and the adjusting mechanism composed of the frame f , the springs sp , the tension-screws s'' , 110 the frame f , bolted to the slide s , and the adjusting-screws s' , all combined substantially as 115 described.

In witness whereof I have hereunto set my hand this 1st day of February, 1886.

WILLIAM M. DICKERSON.
